(57) **CLAIM**

The ornamental design for a ceiling fan light kit, as shown and described.

DESCRIPTION

FIG. 1 is a top perspective view of a ceiling fan light kit, shown in the environment of a ceiling fan, showing my new design;

FIG. 2 is a bottom perspective view thereof;

FIG. 3 is a top view thereof;

FIG. 4 is a bottom view thereof;

FIG. 5 is a front view thereof;

FIG. 6 is a rear view thereof;

FIG. 7 is a left side view thereof;

FIG. 8 is a right side view thereof;

FIG. 9 is an enlarged partial view of the bottom view of FIG. 4;

FIG. 10 is an enlarged partial view of the top perspective view of FIG. 1;

FIG. 11 is an enlarged partial view of the bottom perspective view of FIG. 2;

FIG. 12 is an enlarged partial view of the front view of FIG. 5;

FIG. 13 is an enlarged partial view of the rear view of FIG. 6;

FIG. 14 is an enlarged partial view of the left side view of FIG. 7;

FIG. 15 is an enlarged partial view of the right side view of FIG. 8; and,

FIG. 16 is an enlarged partial view of a portion of the enlarged view of FIG. 15.

Portions of the ceiling fan light kit and the ceiling fan environment are shown in broken lines, which form no part of the claimed design.

1 Claim, 14 Drawing Sheets
